(57) **CLAIM**

The ornamental design for a kids dress up storage, as shown and described.

DESCRIPTION

FIG. 1 is a perspective view of a kids dress up storage showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is another perspective view thereof with a mirror and two storage boxes.

A bottom view is omitted since the bottom view is invisible in normal use.

The broken lines depict portions of the kids dress up storage in which the design is embodied that form no part of the claimed design.
